UNITED STATES PATENT OFFICE.

THOMAS B. DOOLITTLE, OF BRIDGEPORT, CONNECTICUT.

COMBINED ANNUNCIATOR AND SPRING-JACK.

SPECIFICATION forming part of Letters Patent No. 339,627, dated April 13, 1886.

Application filed November 28, 1885. Serial No. 184,141. (No model.)

To all whom it may concern:

Be it known that I, THOMAS B. DOOLITTLE, residing at Bridgeport, in the county of Fairfield and State of Connecticut, have invented 5 certain Improvements in a Combined Annunciator and Spring-Jack, of which the following is a specification.

My invention relates to an instrument for use in telephone-exchanges; and it consists of 10 the combination of a switch or spring-jack and an indicating-instrument or annunciator.

The object of my invention is to make a 15 combination-instrument susceptible of adaptation to any of the various arrangements of circuits which are assembled to constitute a telephone-exchange. The instrument embodies all requisite central-office equipment for a single circuit and a series of such instruments or "units" form a central-office switch-board.

An important feature of my improvement 20 consists in so arranging the instrument that the circuit of which it normally forms part may be readily connected or disconnected with it. For this purpose I provide two insulated plug-sockets, which are placed in the frame of the instrument, and at which the electrical connections of the said instrument terminate. These sockets are each provided 25 with a female screw to receive the male screw formed upon the end of a flexible cord-tip, which forms the terminal of a line-wire. If the instrument is to be used upon a metallic circuit, the cord-tips forming the terminals thereof are placed in position in the two insulated 30 sockets respectively; if upon a ground return-circuit the line-wire cord-tip is connected to one insulated socket and a ground-wire cord-tip to the other. In case of metallic circuits where one side or half of the circuit 35 becomes injured or defective, a single wire may thus be readily substituted for the damaged portion. The necessity for rejecting the whole circuit is thereby avoided. This improvement facilitates the adaptation of the instrument to use upon any circuit.

In some telephone-exchange systems the annunciator is retained in the circuit during the process of oral communication to serve the purpose of a "clearing-out" drop. In other 40 systems it is excluded from circuit.

My combination-instrument is so arranged 45 and constructed that either system may be

used, the change from one to the other only requiring a single easily-executed variation in the electrical connections of the instrument, which may be readily made without the use of special tools.

The spring-jack plugs, for use with flexible conducting-cords having either one or two conductors, are of improved construction. 55 Heretofore such plugs have been employed; but they have been of such a construction that the junction between the end of the flexible conductor and the contact-point of the plug was necessarily soldered, twisted, or wrapped, 60 and in case of double conductor-cords there frequently occurred a cross or short circuit inside the plug-handle where the insulation of the flexible conductors was removed.

In my improved form of plug I provide a 65 passage in the plug-handle to receive the end of the conductor, which passage communicates with the contact-point of the plug. At the junction between this passage and the contact-point there is a screw, which may be 70 separate and independent, or may be formed of independently-movable portions of the plug, the end of the flexible conductor being placed under this screw. The said screw or screw-connected parts are screwed firmly 75 down, thus securely holding the conductor in electrical contact with the plug terminal or tip. Where the plug is for use upon a double conducting-cord, two passages are provided 80 extending longitudinally through the handle, 85 but separate and independent, insulated from each other and terminating at the respective contact-points of the plug, where screws, having bearings in the handle, are provided to hold the conductor-terminals in secure electrical 90 contact with the contact-points of the plug respectively. In the double contact-plug one contact-point is a metal rod placed within but insulated from a metal tube forming the other contact-point. The former projects slightly beyond the latter to make contact with the separable contact-points in the 95 spring-jack.

Referring to the accompanying sheet of drawings, Figure 1 is a view of the instrument 100 complete, with plugs in position. Figs. 2, 3, 4, and 5 show modifications in the electrical connections, designed to adapt the instrument to various exchange systems. Figs. 6 and 7

are the double and single contact-spring jack-plugs respectively, embodying the improved features above described.

F is a metal frame upon which the parts are secured. Upon its front face is hinged at h an annunciator-drop, A.

m is an electro-magnet having polar extensions of well-known form. An armature, B, is pivoted at the rear of the frame, its free end being hooked at n to hold the drop A in position, while said armature retains its normal or retracted position.

a is a flexible spring or electrical contact-point, making electrical connection with spring b. Both points are insulated from frame F by the rubber plate i. The free end of a is so placed with respect to the plug socket or opening q in the frame F, that the point of a jack-plug inserted in q will raise spring a from its resting position on b.

At the rear right-angled extension of frame F there are two insulated metal plug-sockets, j and k. These sockets are intended to receive the plugs p, which form the terminals of main lines. The sockets are preferably screw-threaded to receive a screw-thread upon the end of a cord-tip. By this means the possibility of the loosening or disconnection of the plug is obviated.

If it is desired to use the instrument on a single ground return-line, the plug p forming the terminal of that line is inserted in socket j, and a plug, p, connected to earth, is placed in k. If it is desired to place the instrument upon a metallic circuit, the plugs p forming the terminals of the direct and return conductor, respectively, are placed in the sockets j and k. The benefit derived from this arrangement will be seen when, for instance, one side of the metallic circuit is broken or becomes in any way defective. The defective portion may be readily removed by withdrawing its plug, and another wire may be substituted by inserting the proper plug. The socket q for the spring jack-plug will receive the double plug P, Fig. 6, or the single plug P', Fig. 7.

In Fig. 6 the double contact-plug P is for use on metallic circuits, and consists of an insulating-handle, l, longitudinally perforated with two distinct and separate passages for the two conductors. t is a metal contact-point to connect with the plug socket q of the jack-frame. It is longitudinally perforated, and a rod of metal, t', forming the second contact, designed to engage with spring a, is fixed within t, but insulated therefrom, as by hard rubber r. The inner ends of these two contact-points terminate in the two longitudinal passages in the handle respectively. Screws s and s' are located at this junction in position to screw down upon and hold the end of flexible conductors, introduced through the longitudinal passages in the handle, in electrical contact with the respective contact-points.

In Fig. 7 the single conductor-plug P' is

composed of an insulating-handle, I, longitudinally perforated, a metal contact-point, T, and a screw, S, also longitudinally perforated and placed within the handle, through which the conductor is passed to the junction between the passage or perforation and the plug-tip, where the screw S is screwed down upon and holds said conductor in electrical contact with the tip T.

The electrical connections of this instrument and the variations therein provided for in the construction are best seen by reference to Figs. 2, 3, 4, and 5, and in these figures the screws marked a and b represent the springs similarly marked in Fig. 1. c is an uninsulated screw-post in connection with frame F. It is designed to furnish a means for adapting the instrument to use on a metallic circuit, and by variations in the electrical connections, as shown in Figs. 2, 3, 4, 5, provides for either retaining or excluding the magnet from circuit according to the existing or desired practice.

Figs. 2 and 3 show connections for use where the instrument is normally located upon and forms part of a metallic circuit, the connections shown in Fig. 2 being so arranged that when a double contact-plug is inserted the electro-magnet m will be cut out. In this case the circuit normally enters at j, passes to spring a, to spring b, (a and b being in contact, as in Fig. 1,) through magnet m, to post c, to post k. When a double contact-plug is inserted contact is made between one point of the plug and the spring a, and between the other point of the plug and the socket q; circuit passes via the elements j a t', connected circuit or instrument t q c k, thus excluding the magnet m.

In Fig. 3 connections are so varied that when the plug is inserted the magnet is retained in the metallic circuit.

In Figs. 4 and 5 the connections are varied to adapt the instrument to use upon a ground return-line. In the first instance the magnet is excluded from circuit upon introducing the single conductor-plug P'. In the second instance, the magnet remains in circuit during the process of conversation.

It is to be noticed that this adaptation of the instrument to single or double conductor-circuits and its adaptation to an arrangement of electrical connections, which either excludes or includes the magnet upon the introduction of a jack-plug, is due to the use of two insulated screw-posts or plug-sockets with an uninsulated post.

What I claim, and desire to secure by Letters Patent, is—

1. In a spring-jack, a pair of separable contact-points in position to make electrical contact with the contact point or points of an appropriate spring-jack plug, combined with one or more fixed plug-sockets electrically connected to the terminals of the instrument to receive the cord tips or pins forming the terminals of that main-line circuit of which

the spring-jack is intended to normally form a part.

2. The combination, upon one frame or base, of an indicating-instrument, and a spring-jack 5 consisting of a pair of separable contact-points, with one or more fixed plug-sockets, electrically connected to the terminals of the instrument, which are adapted to receive cord tips or pins forming the terminals of that 10 main-line circuit of which the said instrument is intended to normally form a part.

3. The combination, in one instrument, of an annunciator with a spring-jack having a 15 pair of separable contact-points arranged to form the terminals of the metallic circuit which normally includes said contact-points and the annunciator-magnet, a plug having two contact-points making electrical contact with the terminals of the metallic circuit, and 20 electrical connections, substantially as described, so arranged that the insertion of the plug removes the magnet from circuit

4. The combination, upon a metallic frame, of an electro-magnetic annunciator, a spring-jack consisting of one or more contact-points 25 in position to make electrical contact with the contact point of an appropriate jack-plug, one or more insulated wire terminals to receive the terminals of the main circuit of which the said instrument normally forms part, and an 30 uninsulated screw-post located on the said frame, substantially as and for the purposes set forth.

In testimony whereof I have signed my name to this specification, in the presence of two sub- 35 scribing witnesses, this 23d day of November, 1885.

THOMAS B. DOOLITTLE.
